LAWN MOWER HOUSING

William C. Egloff, Anoka, Kenneth E. Erickson, Minneapolis, Donald A. Larson, St. Paul, and Donald W. Hengel, Minneapolis, Minn., assignors to Foley Manufacturing Company, Minneapolis, Minn., a corporation of Minnesota

Filed Oct. 13, 1959, Ser. No. 57,918

Term of patent 14 years

(Cl. D40—1)

FIG. 1

FIG. 2

FIG. 3

FIG. 4

FIG. 5

Fig. 1 is a view in perspective of a lawn mower housing showing my new design;

Fig. 2 is a view in top plan thereof;

Fig. 3 is a view in front elevation thereof;

Fig. 4 is a view in rear elevation thereof;

Fig. 5 is a view in side elevation thereof as seen from the left with respect to Fig. 1; and

Fig. 6 is a view in side elevation thereof as seen from the right with respect to Fig. 1.

The broken lines shown in Figs. 3, 4 and 5 are for illustrative purposes only.

We claim:

The ornamental design for a lawn mower housing, as shown and described.
